UNITED STATES PATENT OFFICE.

TOWNSON HAND, OF ORLANDO, FLORIDA.

SHOCK-ABSORBER.

1,071,518.

Specification of Letters Patent. Patented Aug. 26, 1913.

Application filed June 8, 1913. Serial No. 771,385.

To all whom it may concern:

Be it known that I, TOWNSON HAND, a citizen of the United States, and a resident of Orlando, in the county of Orange and 5 State of Florida, have made certain new and useful Improvements in Shock-Absorbers, of which the following is a specification.

My present invention relates to shock absorbers or devices adapted to take up or 10 resist vibratory movement of relatively movable parts, particularly vehicle bodies and their axles, whereby a violent vibratory movement of the parts is prevented, and the object of my invention is to provide a device 15 novel in certain respects to be hereinafter particularly pointed out.

In the accompanying drawings which illustrate my invention, the figure is a longitudinal sectional view taken through my invention and illustrating their practical 20 application to a vehicle.

Referring now to this figure, the axle *a* of a vehicle *A* is preferably provided with a depending roller *a'* about which a flexible 25 element *B* is extended, the upper forward end of said flexible element being projected through a central aperture in the base of the upright spring cylinder *C* and connected to a disk *c* movable within the cylinder. The 30 upper end of the cylinder *C* is rigidly secured to the base of the vehicle body as shown, and contains a compression spring *c'* disposed therein between the disk *c* and the base of the cylinder and upwardly through 35 the coils of which the before mentioned end of the flexible element *B* extends. The opposite end of the flexible element *B* is passed rearwardly over a roller *b* journaled in the lower end of a bracket *b'* rigidly attached to the vehicle body and the extremity 40 of flexible element *B* is passed through a central aperture in the forward end of a cylindrical casing *D* and connected to the forward end of a spring cylinder *E* movable 45 within said casing. The casing *D* of the spring cylinder has a threaded connection at its rear end to the forward end of a closed fluid containing cylinder *D'*, these cylinders being thus connected in axial alignment and 50 being disposed longitudinally beneath the vehicle body and connected thereto by straps *d*. The forward end of the fluid cylinder *D'* is provided with a stuffing box *d'* through which projects a piston rod *F*, the forward 55 end of which is movably extended into the spring cylinder *E* and provided at its ex-

tremity with a disk *f*, and the rear end of which, within the fluid cylinder *D'*, is provided with an apertured piston head *f'* and a disk *f''* adjacent said piston head. Around the rod *F* between its forward disk *f* and the rear inner end of the spring cylinder *E* is coiled a spring *e*, a second spring *f''* being coiled about the rod between its rear piston head *f''* and the forward closed end of the fluid cylinder *D'*. Thus when, due to unevenness of the roadway, the axle *a* suddenly lowers away from the vehicle body, the shock of such movement will be resisted and absorbed by means of the several 65 springs *e'*, *e* and *f''*, the spring cylinder *e* being drawn forwardly in the casing *D* against the tension of both of the springs *e* and *f''*.

The piston head *f'* has a surrounding ring *f''* and is provided with a valve disk *f'''* which is prevented from seating rearwardly by means of adjustable abutting members *f''* threaded through the piston head in the path of the valve disk, but which is permitted to seat forwardly in the piston head and thus resist the passage of fluid when the piston head moves rearwardly.

From this it will be seen that when the 85 axle rises, the rearward movement of the piston rod *F* to normal position will be even and comparatively slow, preventing undue wear of the parts and promoting an elastic action throughout.

I claim:

1. The combination with a vehicle and its axle, of a shock absorber comprising a pair of spring cylinders located forwardly and rearwardly of the axle, the forward spring cylinder being rigidly attached to the vehicle body and depending therefrom, a flexible element provided with a disk movable in the forward spring cylinder, a spring between the disk and the base of the said forward spring cylinder, said flexible element being extended beneath and rearwardly of the vehicle axle and having its rear end attached to the rear spring cylinder, a casing secured to the vehicle body and within which the rear spring cylinder is mounted for movement, a fluid cylinder aligned with the casing and having its forward closed end connected thereto, a piston rod movably mounted through the forward closed end of the fluid cylinder and through the rear end of the said rear spring cylinder, a

- disk mounted on the forward end of the piston rod within the said spring cylinder, a spring disposed between the said disk and the rear end of the spring cylinder, a 5 disk mounted on the rear portion of the piston rod, a spring coiled between said last-mentioned disk and the forward closed end of the fluid cylinder, and an apertured piston head mounted on the rear end of the piston rod within the fluid cylinder and having a valve adapted to resist movement 10 of fluid through the piston head when the latter moves rearwardly in the cylinder.
2. In a shock absorber, the combination 15 of a spring cylinder, a casing in which the spring cylinder is movable, a connecting member extending through one end of the casing and having connection with the adjacent end of the spring cylinder, a fluid cylinder having one closed end thereof connected to the opposite end of the casing, a piston rod journaled through the said closed 20 end of the fluid cylinder and through the opposite end of the spring cylinder, disks secured upon the piston rod within the fluid cylinder and within the spring cylinder, 25 springs between the said disks and the adjacent ends of the fluid cylinder and spring cylinder, and a valved piston head carried by the piston rod within the fluid cylinder, the valve of which is arranged to close when the piston head moves in a direction away from the said spring cylinder.
3. In a shock absorber, the combination of a fluid cylinder having closed ends and 30 a casing connected to one end of the fluid cylinder, a piston rod journaled through the connected end of the fluid cylinder and extending within the said casing at one end, a member movable within the casing 35 and having a flexible connection with the respective end of the piston rod, a spring within the fluid cylinder to resist movement of the piston rod in one direction, and a valved piston head carried by the rod within the fluid cylinder to resist movement of the rod in the opposite direction.

TOWNSON HAND.
